United States Patent

Des. 242,414

Patented Nov. 23, 1976

242,414

COMBINED TIE AND BELT HANGER

Mack Salladay, Pittsburgh, Pa., assignor to
Action Industries, Inc., Cheswick, Pa.

Filed May 10, 1976, Ser. No. 684,656

Term of patent 14 years

Int. Cl. D6—08

U.S. Cl. D6—251

Fig. 2

Fig. 1

FIG. 1 is a front elevational view of a combined tie and belt hanger showing my new design; and

FIG. 2 is a side elevation view taken from the left of FIG. 1.

The rear of the hanger is a mirror image of the front.

I claim:

The ornamental design for a combined tie and belt hanger, as shown and described.
